O.C. Laramore*

WITNESS:

William C. Sloan
INVENTOR

BY *Victor J. Evans*

ATTORNEY

UNITED STATES PATENT OFFICE.

WILLIAM C. SLOAN, OF CAMDEN, NEW JERSEY.

ICE REMOVER.

Application filed February 25, 1924. Serial No. 695,105.

To all whom it may concern:

Be it known that I, WILLIAM C. SLOAN, a citizen of the United States, residing at Camden, in the county of Camden and State 5 of New Jersey, have invented new and useful Improvements in Ice Removers, of which the following is a specification.

This invention relates to improvements in devices for removing ice from trolley 10 wires and has for an object the provision of a novel and efficient wire engaging member for this purpose, which will act to scrape the wire and to agitate the same sufficiently to remove the ice from the entire 15 circumference of the wire.

Another object of the invention is the provision of means for removably securing the wire engaging member and its operating means to the trolley arm, so that the same 20 may be conveniently attached or removed.

With the above and other objects in view, the invention further includes the following novel features and details of construction, to be hereinafter more fully described, ill- 25 lustrated in the accompanying drawings and pointed out in the appended claims,

In the drawings:—

Figure 1 is an elevation showing the invention in use.

Figure 2 is an edge view of the same.

Figure 3 is a sectional view on the line 3—3 of Figure 1.

Figure 4 is a fragmentary perspective view of a portion of the rim of the rotatable member.

Figure 5 is a detail perspective view of one of the scraper elements.

Referring to the drawings in detail wherein like characters of reference denote cor- 40 responding parts, the reference character 10 indicates a portion of the usual trolley arm which is carried by a car and to which the trolley wheel is attached, while the trolley wire is indicated at 11.

The invention which is designed to be removably secured to the arm 10 comprises a frame 12. This frame includes a base or platform 13 from which depends a plate 14, the lower edge of this plate being ar- 45 ranged at an incline with respect to the base and carrying substantially semi-circular clamps 15. These clamps are adapted to engage around the arm 10 and when so engaged will maintain the platform 13 sub-

stantially horizontal, suitable means such as bolts 16 being provided for securing the clamp to the arm.

The frame 12 further includes vertically disposed spaced bearing standards 17 which rotatably support a shaft 18. This shaft 60 has secured thereon a wheel 19 of suitable insulating material. This wheel is of novel construction and comprises a removable sectional metal rim 20 which is provided with radially disposed lugs 21, the sections of 65 the rim being secured together and to the wheel 19 by screws or similar fastening devices 22.

The lugs 21 have bolted or otherwise secured thereto scraper elements 23 which are 70 adapted to engage the wire 11 and are so shaped as to scrape the ice from the wire. For this purpose the elements are substantially hook-shaped and are provided at their outer ends with outwardly received trans- 75 versely curved cutting edges 24 which engage a scraper along the under surface of the wire. In addition, these elements 23 impart a certain amount of agitation to the wire 11 so that as the ice is removed from 80 the lower portion of the wire by a scraping action the remainder of the ice around the circumference of the wire will be shaken therefrom.

Also secured upon the shaft 18 is a sprocket wheel 25 which is connected by means of a chain 26 with a sprocket wheel 27 se- 85 cured to the shaft of a motor 28, the latter being mounted upon the platform 13 within the frame 12.

Pivottally mounted upon the platform is an arm 29 which is urged upward to engage the trolley wire by means of a spring 30. This arm carries a trolley wheel 31 and sup- 90 plies current for the operation of the 95 motor 28.

It will be apparent from the foregoing de- 100 scription and accompanying drawings that the invention provides an exceedingly sim- ple and efficient device which may be remov- 105 ably secured to the trolley arm to effectually remove ice from the trolley wire.

The invention is susceptible of various changes in its form, proportions and minor details of construction and the right is 105 herein reserved to make such changes as properly fall within the scope of the ap- pended claims.

Having described the invention what is claimed is:—

1. An ice remover for overhead trolleys comprising in combination with the trolley arm of a car, a rotatable trolley wire engaging member, means for rotating said member, and means for removably securing said member and its rotating means to said arm.
2. An ice remover for overhead trolleys comprising in combination with the trolley arm of a car, a rotatable trolley wire engaging member including spaced hook-shaped cutting elements, means for rotating said member and means for removably securing said member and its rotating means to said arm.
3. An ice remover for overhead trolleys comprising in combination with the trolley arm of a car, a motor supporting frame, means for removably securing the frame to said arm, a motor supported upon the frame,

a rotatable trolley wire engaging member mounted upon the frame, means operatively connecting the motor and rotatable member, whereby the latter may be operated and means whereby current may be supplied to the motor from the trolley wire.

4. An ice remover for overhead trolleys comprising in combination with the trolley arm of a car, a motor supporting frame, means for removably securing the frame to said arm, a motor supported upon the frame, a rotatable trolley wire engaging member mounted upon the frame, means operatively connecting the motor and rotatable member, whereby the latter may be operated and a pivotally mounted spring actuated trolley wire engaging arm carried by the frame, whereby current may be supplied to the motor from the trolley wire.

In testimony whereof I affix my signature.
WILLIAM C. SLOAN.
